UNITED STATES PATENT OFFICE

HOWARD M. BARBER, OF PAWCATUCK, CONNECTICUT, ASSIGNOR TO C. B. COTTRELL & SONS COMPANY, OF WESTERLY, RHODE ISLAND, A CORPORATION OF DELAWARE

ROTARY PRINTING PRESS

Application filed May 18, 1928. Serial No. 278,672.

The object of my invention is to provide means whereby the form cylinder may be independently adjusted both rotatively with respect to its driving means and in an endwise direction, especially while the press is running, so that the form on the cylinder may be brought into proper register easily and quickly; thereby obviating the necessity of shifting the form on its cylinder, which latter must be done while the press is at rest and at a considerable loss of the printing time.

This invention is directed, more specifically, to the provision of the two adjusting mechanisms, one on one side of the press frame and the other on the other side of the press frame, as distinguished from my co-pending application executed and filed of even date herewith, its Serial Number being 278,671 in which both adjusting mechanisms 20 are located on the same side of the press frame.

A practical embodiment of my invention is represented in the accompanying drawings, in which

Fig. 1 represents a detail transverse vertical section through the printing press at the form cylinder.

Fig. 2 represents a detail view looking toward one side of the press frame.

Fig. 3 represents a detail view looking toward the other side of the press frame.

The form cylinder 1 of the printing press has the oppositely projecting ends 2 and 3 of its shaft rotatively mounted for endwise movement in suitable bearings 4 and 5 in the sides 6 and 7 respectively of the printing press frame.

The spiral wide faced form cylinder gear 8 is slidably interlocked with the end 3 of the form cylinder shaft, in the present instance by making the gear hollow and providing its bore 9 with longitudinal grooves 10 for slidably receiving the feathers 11 secured on the enlarged portion 12 of the shaft end 3 located within said gear.

The form cylinder driving means includes a gear 13 meshing with the form cylinder gear 8.

The mechanism for adjusting the form cylinder rotatively with respect to its driving means while the press is running is located

at one side of the press frame and is constructed, arranged and operated as follows:

The upper end of the form cylinder gear 8 is provided with a plate 14 having a trunnion 15 on which is loosely mounted one arm 16 of a yoke, a cap 17 secured to the end of said trunnion 15 serving to cause the form cylinder gear 8 to be moved across the face of the driving gear 13 by the movement of the yoke. A hand screw shaft 18 is rotatively mounted in the hub 19 of the yoke against endwise movement with respect thereto and said hand screw shaft has a screw-threaded engagement with the side frame 7. The yoke is guided in its movement by providing its arm 20 with a sleeve 21 slidably mounted on a pin 22 carried by and projecting from the side frame 7. The hand shaft 18 may be provided with a suitable hand wheel 23 for manipulating it.

The mechanism for adjusting the form cylinder in an endwise direction while the press is running without disturbing its rotative adjustment, is located upon the other side of the printing press frame and is constructed, arranged and operated as follows:

A hand screw shaft 24 has a screw-threaded engagement with the side frame 6 and is rotatively interlocked with the hub 25 of a yoke, the arm 26 of which is rotatively interlocked with the form cylinder shaft end 2. The yoke is guided in its movements by providing its arm 27 with a sleeve 28 slidably engaged with a pin 29 carried by and projecting from the side frame 6. The hand shaft 24 is provided with a suitable hand wheel 30 for manipulating it.

From the above description it will be seen that the form cylinder shaft may be rotatively adjustable with respect to its driving means by moving the form cylinder gear 8 across the face of the driving gear 3 by the manipulation of the hand screw shaft 18 at one side of the press frame. It will also be seen that the endwise adjustment of the cylinder can be provided for by the manipulation of the hand screw shaft 24 at the other side of the press frame.

It is evident that various changes may be resorted to in the construction, form and arrangement of the several parts without de-

parting from the spirit and scope of my invention; hence, I do not wish to be limited to the particular embodiment herein shown and described, but

5. What I claim is:—

1. In a rotary printing press, a form cylinder, its spiral gear, a driving gear meshing therewith, and manually operated mechanisms located on opposite sides of the press for moving the form cylinder gear across the face of its driving gear to adjust the rotative position of the form cylinder and for adjusting the form cylinder endwise without changing the position of the form cylinder gear.
10. 2. In a rotary printing press, a form cylinder, its shaft, a form cylinder spiral gear slidably interlocked with said shaft, a driving gear meshing with said form cylinder gear, and manually operated mechanisms located on opposite sides of the press for moving the form cylinder gear across the face of its driving gear to adjust the rotative position of the form cylinder and for adjusting the form cylinder endwise without changing the position of the form cylinder gear.
15. 3. In a rotary printing press, a form cylinder, its shaft, a form cylinder spiral gear slidably interlocked with said shaft, a driving gear meshing with said form cylinder gear, yokes connected to the form cylinder gear and shaft respectively, and hand screw shafts located on opposite sides of the press and connected to their respective yokes for moving the form cylinder gear across the face of its driving gear to adjust the rotative position of the form cylinder and for adjusting the form cylinder endwise without changing the position of the form cylinder gear.
20. 4. In a rotary printing press, a frame, a form cylinder, its shaft, a form cylinder spiral gear slidably interlocked with said shaft, a driving gear meshing with said form cylinder gear, yokes connected to the form cylinder gear and shaft respectively, a hand screw shaft rotatably interlocked with one of said yokes and having a screw-threaded engagement with the frame at one side of the press for moving the form cylinder gear across the face of its driving gear to adjust the rotative position of the form cylinder with respect to said driving gear and another hand screw shaft rotatively mounted in the other yoke on the opposite side of the press and having a screw-threaded engagement with the frame for adjusting the cylinder endwise without changing the position of the form cylinder gear.
25. 5. In testimony that I claim the foregoing as my invention, I have signed my name this 16th day of May, A. D. 1928.

HOWARD M. BARBER.
